Lacy & Lacy, Attorneys.

UNITED STATES PATENT OFFICE.

ARTHUR T. KUEHNÉR, OF ELKRIDGE, MARYLAND.

COMBINED CAR-DOOR LOCK AND OPENER.

Application filed August 7, 1920. Serial No. 401,884.

To all whom it may concern:

Be it known that I, ARTHUR T. KUEHNÉR, citizen of the United States, residing at Elkridge, in the county of Howard and 5 State of Maryland, have invented certain new and useful Improvements in Combined Car-Door Locks and Openers, of which the following is a specification.

This invention relates to an improved car 10 door lock and opener and has as one of its principal objects to provide a device of this character which may be readily applied to a car door of substantially any conventional design and which will serve to securely 15 fasten the door closed.

A still further object of the invention is to provide a device which may be operated for partially opening the door so that a hand may be inserted between the forward 20 end of the door and the door jamb for grasping the door and thus readily completing the opening movement thereof.

And the invention has as a still further object to provide a device which, after the 25 door has been closed, will operate to bind the door against the door jamb so as to maintain a closed joint therebetween.

Other and incidental objects will appear hereinafter.

30 In the drawings:

Figure 1 is a perspective view showing my improved device applied to a car door of conventional design.

Figure 2 is a plan view showing the device on a somewhat enlarged scale,

Figure 3 is a plan view of a slightly modified form of the invention, and

Figure 4 is a longitudinal sectional view taken medially through the modified structure.

Referring now more particularly to the drawings, I have shown my improved device in connection with a car door of conventional design. The door is indicated at 45 10 and the door jamb at 11, this door jamb being formed by a sealing plate substantially Z-shaped in cross section. About the margins of the door is fixed a metal frame 12 the members of which, as suggested in 50 Figure 4, provide sealing strips for the door, similar strips, typified by the strip

forming the door jamb 11, being secured about the door opening.

In carrying the invention into effect, I employ a base plate 13 which is bolted or otherwise secured to the door and is provided at its lower edge with an outwardly projecting apertured stop lug 14. Rising from the forward end portion of the plate is a headed pivot stud or post 15 and 60 mounted to swing upon said post is an operating lever 16. At its forward end this lever is formed with a depending arcuate finger or lug 17 and rising from the lever above said lug is an arcuate cam lug 18 reinforced at its rear side by a suitable reinforcing web 19. The convex forward face of this lug provides, of course, a cam face and, as will be observed, this face merges gradually with the forward face of the lug 70 17 to provide an arcuate crotch therebetween lying in a plane axially of the lever. Formed on the lower edge of the lever to mate with the lug 14 of the base plate, is an apertured stop lug 20 adapted to abut 75 the former lug for limiting the lever in its downward swinging movement to horizontal position, and depending from the lever at the plane of the pivot stud 15 is an arm 21 the lower end portion of which is directed laterally at substantially right angles and is apertured to freely receive the eye of a hasp 22.

Upon the door jamb 11 is fixed a lock stand 23 shaped to fit the Z-shaped strip forming said jamb. As will be noted, the stand is of skeleton construction and is formed with angularly disposed portions one of which seats against the base flange of said strip and receives a bolt or other suitable fastening device 24. Extending from the other of the angularly disposed portions of the stand are oppositely directed vertical lugs 25 and engaged through these lugs are bolts or other suitable fastening devices 26 cooperating with the bolt 24 for firmly securing the stand in position. Rising from the outer face of the stand medially thereof is a headed post 27 fitting in the crotch of the lever 16 between the lugs 17 and 18 and extending from the stand in advance of this post are vertically aligned

apertured lugs which, for convenience, have been indicated at 28 and 29 respectively. As will be noted, the hasp 22 is designed to fit over the lug 29 and slidably fitted 5 through the lugs is a headed locking pin 30 securing the hasp against displacement. As particularly brought out in Figure 2, the lower end portion of the locking pin is preferably reduced somewhat in diameter 10 and accordingly, the opening through the lug 29 is somewhat smaller than the opening through the lug 28 and to prevent upward displacement of the pin through this latter lug, the upper end portion of said 15 pin is provided with lateral stop spurs 31. Through the lower end portion of the pin is a slot through which may be engaged a seal, as conventionally illustrated at 32. Thus, as will be seen, the door will be effectively locked closed and can be opened only 20 by breaking the seal 32 and lifting the locking pin 30 to release the hasp 22.

As will now be readily understood in view of the preceding description, when the hasp 22 is released as previously indicated, and 25 swung free of the lug 29 of the lock stand, the lever 16 may be swung upwardly for riding the cam lug 18 against the post 27 and consequently shifting the door away from 30 the door jamb. As will be appreciated, the forward edge of the door may then be grasped so that the door may be readily opened. At present considerable difficulty 35 is experienced in starting an ordinary car door in its movement to open position due to the difficulty of obtaining an adequate hold upon the door. In the present device this difficulty is effectually overcome since, as will be seen, the lever 16 of the device may 40 be quickly and easily forced upwardly to produce a crack between the forward edge of the door and the door jamb. This done, a hand of the operator may be readily inserted through the crack to engage the door for 45 forcing the door open.

In Figures 3 and 4 of the drawings, I have illustrated a slight modification of the invention. Referring particularly to these 50 figures, it will be seen that a base plate 33 is employed. From the base plate extends a pivot stud 34 upon which is pivoted an operating lever 35. At its forward end this lever is provided with a cam lug 36 while 55 from the lower edge of the lever extends an apertured lug 37 mating with a similar lug 38 projecting from the base plate. Secured to the door jamb is a lock stand 39 from which projects a headed post 40. All of this 60 structure, as just described, is identical with the preferred form of the invention.

As will now be observed upon particular reference to Figure 3, the arm 21 and hasp 22 of the preferred construction are eliminated, and in lieu thereof the lug 17, as em-

ployed in the preferred construction, is elongated to provide a substantially semi-circular locking lug 41 adapted to extend beneath and embrace the post 40 of the lock stand. Consequently, when the lever 35 is 70 disposed in horizontal position, said lug will coact with the post for securing the door against opening movement. Thus, the lugs 28 and 29 as well as the locking pin 30 of the preferred construction, are also eliminated in this modified structure. To prevent upward swinging of the lever 35 and accordingly lock the door closed, a lock, as conventionally illustrated at 42, is engaged 75 with the apertured lugs 37 and 38. As will be seen, this modified form of the invention also provides a highly effective structure. The cam lug 36 will, of course, coact with the post 40, when the lever 35 is swung upwardly, for forcing the door away from the door jamb so that the door may be readily opened. Further, attention is directed to the fact that when the door is closed and the lever is swung downwardly to its normal horizontal position, the lug 41 will 80 coact with the post for binding the door closed.

Having thus described the invention, what is claimed as new is:

1. The combination with relatively fixed and movable members, of a fixed element carried by one of said members, and a lever pivoted upon the other of said members and provided at a point spaced beyond the pivotal center thereof with an operating foot having a curved heel portion extending in a direction around said element and a diverging toe portion having a cam face rising above the element to coact therewith throughout the length of said face whereby the lever may be swung for shifting the movable member away from the fixed member, the heel and toe portions forming a crotch therebetween normally abutting said element. 95

2. The combination with relatively fixed and movable members, of a headed post carried by one of said members, and a lever pivoted upon the other of said members and provided at its forward end at a point spaced beyond the pivotal center of the lever with diverging lugs forming a crotch therebetween coacting with the post beneath the head thereof, one of said lugs extending in a direction around the post and the other of said lugs being provided with a cam face overhanging the post whereby the lever may be swung for causing said face to coact with the post and shift the movable member away from the fixed member. 100

3. The combination with relatively fixed and movable members, of a stand carried by one of said members and provided with a post, a lever pivoted upon the other of said members and provided at its forward end at 105

a point spaced beyond the pivotal center of the lever with an upstanding lug having a cam face extending upwardly over the post whereby the lever may be rocked upwardly 5 for causing said face to coact with the post and shift the movable member away from the fixed member, the lever being provided

near the pivot point thereof with an arm, a hasp carried by said arm, and means for connecting the hasp with the stand whereby to lock the lever against upward swinging movement.

In testimony whereof I affix my signature.

ARTHUR T. KUEHNER. [I. S.]
